UNITED STATES PATENT OFFICE.

HANS VON LITTRÖW, OF CHEMNITZ, AND FRANZ HERMANN ZEHL, OF BIEBRICH-ON-THE-RHEIN, GERMANY.

WINDSHIELD WIPER.

Application filed March 20, 1926. Serial No. 96,195.

The present invention has for its object an apparatus for cleaning the panes and window-screens or glasses on vehicles of any kind.

For the purpose of cleaning such panes and window-screens on vehicles of any kind and for removing from them any hard crusts of ice and frozen snow, as will be found on the window-panes and window-screens of locomotives, ships, motor-cars and the like various constructions of cleaning apparatus have been proposed. To this end, for example, wipers have been used which were made of rubber yielding per se or by means of metal springs and intended to remove any moist deposit or rain-drops from the windows and furthermore corrugated or toothed layers such as metal brushes or knife-like metal strips have been arranged in such a manner that these metal layers or strips will come into touch with and act on the window-panes and glasses together with the rubber during an increased pressure on the wiping device.

Said combined arrangements of rubber-layers on the one hand and metal-layers or knife-like metal strips on the other hand in connection with wipers however have the disadvantage that said metal-layers or strips will not be pressed sufficiently and evenly at all points of the window-panes to be cleaned, because first of all the window-panes are rarely entirely plane-parallel and secondly because said window-panes are bent and moved in consequence of the constant movement of the vehicle-body and the window-frame; consequently there will always be bent and uneven parts on the windows where the metal layers or strips can not contact with so as to remove the hard crusts of ice or the like.

The wiping-device according to the present invention has the object of overcoming these disadvantages and is enabled to remove said hard crusts of ice, snow or the like at every point of the panes or window-screens or glasses touched by the wipers. For obtaining this result the wiping-device consists in the combination of single teeth, set or placed loosely adjacent one another, with means for receiving and holding together said teeth forming the ice-remover and with means for forming a yielding bearing for the single teeth.

In consequence of this elastic bearing said teeth are narrow and able to conform to every unevenness of the window-pane and thus remove with certainty any ice-crusts or other hard layers sticking to the window including uneven parts of the pane.

A wiping-device in connection with an apparatus for cleaning window-panes and screens according to the invention is shown in the drawing by way of example.

Fig. 1 represents a plan view of our improved device together with a portion of a window pane.

Fig. 2 represents a detail front elevation, on a larger scale, of a portion of one of the wipers.

Fig. 3 represents a detail section taken in the plane of the line AB of Fig. 4. Fig. 3^a represents a detail section taken in the plane of the line.

Fig. 4 represents a vertical section taken in the plane of the line EF of Fig. 2. Fig. 4^a represents a similar section of a modified form of wiper.

As can be seen from Fig. 1, there are arranged on both sides of the window-pane g, to be cleaned of ice or the like crusts, the channel bars a of the wiping bodies and fixed to levers n which move the wipers to and fro over the window-pane g. For the purpose of moving said levers to and fro on the window-pane g they are set on two spindles passing into each other and having curved handles o, o¹, the latter being so arranged that the inner handle can be moved within the outer. Either by catching hold of both handles or only one of them, both channel bars a or only the one or the other of the channel bars is brought onto the glass-pane g, the cleaning of which on both sides or only on one side is effected by means of alternately turning either both handles o, o¹ or only one of them towards right and left.

Into each channel bar a, a separation-wall b is inserted, subdividing the channel bar into two halves. Into the one half a rubber-ledge c is inserted whereas into the other half there are brought the metal teeth d loosely set or placed next to each other. Said separation-wall b is provided on its side with a longitudinal groove b¹ (Fig. 4) in which on moving the teeth d along the window-pane g to be cleaned, said teeth are

guided by means of the noses *e*, at the same time being protected by the same against falling out. The teeth themselves repose with their bottom ends, which are either pointed or round and inserted into the bar *a*, on a rubber-layer *f* into which said teeth can penetrate with their ends if a strong pressure is exerted onto the teeth against the window-pane. If this pressure ceases the rubber-layer *f* causes a gradual and even return of the teeth into their original position (Fig. 1). The rubber wiper *c* inserted into the other half of the channel bar and preferably having a round top end is set into a U-shaped metal strip *i* bent so as to form a receptacle and is held within the latter by means of the bolts *j*. On the outer side of the metal-strip *i* towards its bottom there are fixed the springs *k* (Fig. 3) which repose on the bottom of the channel bar *a* and press the metal receptacle *i* together with the rubber-wiper *c* towards the window-pane *g* and onto the same. For the purpose of fixing the metal receptacle *i* to the channel bar *a* there are, as will be seen by Fig. 4, provided on said receptacle *i* guiding bolts which extend through the bottom of the channel bar *a* and are kept in position by the cross-bolts *m*.

With a modified form of construction according to Fig. 4^a, the teeth are arranged in alternate opposing relation to each other and they are not guided when moved by noses *e* in longitudinal grooves *b*¹ formed in the separation-wall *b* as in Fig. 4 but each tooth *d* is provided on its part inserted into the receptacle *i* with a longitudinal slot *h*. Through these longitudinal slots a bar or wire *l* riveted to the side-walls of the receptacle *i* is passed, by means of which the teeth are held together when moved.

The bottom ends of the teeth *d* being for example of a round shape also repose on a rubber-layer *f*.

For the purpose of removing from the window-pane a slight deposit of condensed moisture or rain-drops a slight pressure of one or both rubber-wipers *c* against one or both sides of the window-pane *g* is sufficient and on turning the handles of the cleaning apparatus towards right and left one or both wipers will then softly slide

over one side or both sides of the window-pane. If however the window-panes are covered with a hard crust, say of ice or frozen snow, first of all the rubber-wipers *c* will be forced under pressure against the window-panes; on using a still stronger pressure these ledges *c* will recede against the action of the springs *k* so that they get into line with the free ends of the teeth *d* in such a manner that the teeth *d* with their sharp edges come into action and remove with certainty, on moving the channel bars *a* to the right and left, by means of the stronger pressure, the frozen snow or ice-crusts from the window-panes.

To avoid injuring the window-panes on using a stronger pressure the teeth *d* are, in consequence of the reposal of their pointed or rounded ends on the rubber-layer *f*, enabled to penetrate into the latter and thus recede from the window-panes when a high pressure is exerted, the teeth *d* at the same time being either guided by the noses *e* protruding from their sides, in the groove *b*¹ of the separation-wall *b* (Fig. 4) or by means of the longitudinal slots *h* and the bar or wire *l* (Fig. 4^a).

When the strong pressure on the teeth stops the latter again return by the counter-pressure of the rubber-layer *f* into their original position such as is also the case with the rubber-wiper *c* by means of the springs *k*.

In Fig. 3^a towards the right hand side a few teeth *d* are omitted for the purpose of showing the longitudinal groove *b*¹ for guiding the noses *e* (Fig. 4) of the teeth.

What we claim is:

In a wiping-device for cleaning vehicular window-panes arranged on vehicles of any kind, the combination with teeth placed in alignment for removing ice-crusts or the like from the panes, of means for loosely receiving and holding together said teeth and means forming a yielding abutment for the base of the teeth.

In testimony, that we claim the foregoing as our invention, we have signed our names this 20th day of February 1926.

HANS VON LITTROW.
FRANZ HERMANN ZEHL.
